UNITED STATES PATENT OFFICE.

NORMAN HOWARD CAUFIELD, OF VICTORIA, BRITISH COLUMBIA, CANADA, ASSIGNOR
TO CAUFIELD STOOKER COMPANY LIMITED, OF VICTORIA, BRITISH COLUMBIA,
CANADA.

STOOKING MACHINE.

Application filed July 8, 1926. Serial No. 121,215.

This invention relates to improvements in stooking machines, and the object of the invention is to provide a stooking machine designed to transfer the sheaves from the binder to the stooker automatically, and to form the sheaves so delivered efficiently and expeditiously into a stook and then deposit the stook on the ground in a vertical position.

10 A further object is to provide a stooking machine of light, durable and simple construction in which the number of parts is reduced to a practical minimum, and which, in operation, will more efficiently perform 15 all the functions identified with machines of this description.

A still further object is to provide a machine of this character that can be manufactured and placed on the market at a 20 reasonable price.

With the foregoing and other objects hereinafter more fully referred to in detail, and generally speaking, the machine comprises a tiltable sheaf-receiving and shock-25 forming and depositing basket, normally horizontal to receive the sheaves and tiltable to form and dump the stook, in combination with an elevator for receiving the sheaves from a binder and automatically delivering 30 them to the basket, and co-ordinating mechanisms operable on the forward movement of the machine for separately operating the elevator and the basket, and automatic means for simultaneously operating the basket and 35 stopping the elevator, and for automatically and simultaneously stopping the operation of the basket and re-starting the elevator on the basket returning to normal position.

More specifically, the invention comprises, 40 in combination with an elevator adapted to receive the sheaves from the binder and automatically deliver them, a tiltable basket supported on a moving frame in a manner capable of being loaded with sheaves and 45 tilted to dump the stook, the basket being formed with pivotally mounted side plates inwardly and adjustably movable and adapted to swing from a horizontal to approximately a vertical position and having 50 reciprocally operable displaceable bottom and end plates operatively connected to the side plates, mechanism for operating the elevator, and mechanism for operating the

basket, and means continuously operable on the forward movement of the machine 55 for operating said mechanisms separately and so associated with them as to automatically start the elevator and stop the basket on the latter returning to normal loading position.

60 Referring now to the drawings, in which like characters of reference indicate corresponding parts in each figure:

Figure 1 is a plan view of the complete machine;

Figure 2 is a front elevation;

Figure 3 is a rear end view of the machine;

Figure 4 is a side elevation of the machine with elevator shown in dotted lines;

Figure 5 is a view of the opposite side to that shown in Figure 4 with elevator in full lines;

Figure 6 is a plan view of the underside of the elevator and receiving table;

Figure 7 is a side elevation of the guide tracks for the elevator chain;

Figure 8 is a section on line 8—8 of Figure 6;

Figure 9 is a fragmentary plan view showing the track upon which the closure member operates;

Figure 10 is a front elevation of the clutch driving mechanisms;

Figure 11 is a side view of Figure 10;

Figure 12 is a perspective detail of the cam member;

Figure 13 is a perspective detail of the upper half of the closure plate, showing the friction roller attached thereto;

Figure 14 is a perspective detail of the elevator sheaf-carrying arm with crank and roller;

Figure 15 is a section on line 15—15 of Figure 14.

Referring now more particularly to the drawings, in which an example of my improved stooking machine is illustrated, 10 designates the horizontal frame of any suitable form and here shown as substantially 100 U-shaped with an addition or extension 11 on one side, the whole being designed to support the machine structure as hereinafter described.

This frame is provided on the side adjacent the binder with a main traction driv-

ing wheel 13, the opposite side of the frame being supported by an outside wheel 14 and the front of the machine by a pair of front castor wheels 15.

5 Referring first to the drive mechanism, secured to the tractor wheel 13 on the hub thereof and rotatable therewith is a sprocket 16 chain-connected by a chain 17 to a sprocket 18 rotatably mounted on a shaft 19 in turn rotatably mounted on the traction wheel side of the frame and supported by a suitable bearing 20 secured to the frame 10. The sprocket 18 has secured on its inner face a clutch 21 provided with a plurality of 15 spaced slots 22 with any of which a spring-actuated pivotally mounted pawl 23 is adapted to engage. This pawl is mounted on a bracket member 24 rigidly mounted on the shaft 19. The pawl 23 is designed to engage at its lower end with an arm 25 pivotally mounted at 26 on the bracket 24. This arm 25 is in turn designed to rest upon a laterally movable spring-actuated pin 27 on the front end of the frame, the pawl 23 being thereby held out of engagement with the slots 22 of the clutch 21. The pin 27 may be operated manually from the binder seat and any suitable mechanical means may be used, such as a link 28 and lever arm 29, 30 to which a cable 30, as indicated in Figure 2, may be attached.

From the foregoing, it will be seen that on the machine being moved forward with the binder and the tractor wheel 13 rotating the sprocket 16 will be rotated to operate the sprocket 18 and the shaft 19, as the clutch 21 is thrown into or out of gear.

Rigidly mounted on the hub of the tractor wheel 13 in turn mounted on the stub shaft 40 31 is a bevelled gear 32 designed to mesh with a bevelled gear 33 keyed on a shaft 34 at right angles to the stub shaft 31, in suitable bearings 35 in the extension 11 of the frame 10. On this shaft 34 is a sprocket 36 connected by a chain 37 to a sprocket 38 (see Figure 2) mounted on an elevator shaft 39 supported in suitable bearings 40 on an upright portion 41 mounted on the frame 10. This shaft 39 is provided with 45 sprockets 42 and 43 chain-connected by endless chains 44 and 45 to sprockets 46 and 47 on a counter shaft 48 at the lower end of the elevator frame. Intermediate of the shafts and forming an essential feature of my elevator are spaced rods 50 on which are mounted suitably bent prongs 51. These rods, as illustrated more particularly in Figure 14, are pivotally mounted in bracket members 52 rigidly secured to the endless 55 chains 44 and 45 and are crank-shaped at each end as at 53 and provided with rollers 54 adapted to engage with a trackway 55 provided in the elevator casing or frame so that in operation, when the hook or the 60 prong-carrying rods reach a certain point at

the top of the elevator, they will automatically swing downwardly, discharging the sheaf into the guide plate 56, thence into the basket hereinafter more fully described.

In co-operation with these pivotally mounted sheaf conveyor members, I provide on the supports a bail member 57 provided with downwardly extending resilient guide members 58 in staggered relationship to the sheaf-carrying prongs to more accurately 75 guide the sheaves when being discharged therefrom.

It will be noted that, as the prong-carrying rods of the elevator travel upwardly, the prongs will be protruding at substantially right angles to the elevator frame while, as they reach the top, they will automatically swing over, giving an impetus to the sheaves being discharged.

A résumé of the foregoing discloses that on the mechanism being moved forward and the tractor wheel 13 rotated, the gear wheel 32 meshing with the gear 33 will rotate the shaft 34 and through the chain and sprocket thereon connected with the elevator shaft 39, the pivotally mounted prong-carrying rods 50 on the elevator chains 44 and 45 will be operated to engage the sheaves delivered from the binder onto the receiving table 59 and convey them

upwardly and over the apron or guide plate 56 to load them into the basket. Mounted on the sprocket 36 is a spring-actuated pivotally mounted arm 60. This arm is provided with a projecting boss 61 and engaging ends 62. The boss 61 is adapted to engage and disengage the rollers 63 mounted on the clutch member 64 rigidly mounted on the shaft 34 whereby the shaft 34 and the operating mechanism above described for the elevator is thrown into and out of gear.

The ends 62 of the arm 60 are designed to engage with a trip lug 64' protruding from an arm 65 pivotally connected to the frame at 66 and pivotally connected to a vertical arm 67 in turn pivotally connected at 68 to a spring-actuated pivotally mounted dog 69 adapted to engage and disengage with a cam 70 mounted on the shaft 19. Adjacent the opposite end of the shaft 19 and mounted thereon is a locking cam 70' adapted to be engaged by the spring-actuated arm 70' to lock the basket in inoperative position.

From this it will be seen that in normal loaded position the arm 25 will be resting on the spring-actuated pin 27 retaining the pawl 23 out of engagement with the slots 22 and that the basket operating mechanism will be out of gear while the elevator operating mechanism, through the engagement of the boss 61 with the rollers 63 and the disengagement of the ends 62 with the tripping lug 64', will be automatically in gear and in

operation. Consequently, on the required 120

125

130

135

number of sheaves being delivered to the basket and the arm 29 operated, the arm 25 will drop, permitting the pawl or dog 23 to engage with the clutch slots 22 throwing the basket operating mechanism into gear and the elevator operating mechanism out of gear by releasing the spring-held pawl 69 permitting, through the vertical arm 67, the lug 64' to engage with the 5 spring-actuated arm end 62 and thus throw the elevator mechanism out of gear. Then, as the basket mechanism tilts, the basket 10 to form and deposit the sheaves in the form of stooks, and gradually assumes its normal 15 horizontal position, the cam 70, on the shaft 19 having completed one revolution, will automatically engage with the spring-actuated pawl 69, throwing the elevator operating mechanism into gear by disengaging 20 the lug 64' with the end 62 of the arm 60 throwing the basket operating mechanism out of gear by the automatic engagement 25 of the arm 25 with the spring-actuated pin 27.

An important feature in the structure 25 of the mechanism above described is the combination of the trip arm 25 to throw the slotted clutch into operation, and with it the basket operating mechanism of the cam 70, rigidly mounted on the shaft supporting this clutch, and which, simultaneous 30 with the throwing in of the clutch whereby the shaft is rotated, operates the trip for the elevator mechanism to throw it out of gear.

Referring now to the basket 71 which has been previously mentioned but which has not been explained, this and the mechanism for operating it comprise an extension of the shaft 19 through a suitable bearing 72 on the frame and provided on its 10 inner end with a cam 73 and a crank arm 74 while on the opposite side of the frame in a bearing 75 is a stub shaft 76 with a cam 77 and crank arm 78 thereon. Connecting the crank arms is a transversely extending shaft 79 having rigidly mounted thereon crank arms 80 and 81 at each end. The basket proper comprises side plates 82 and 83. These side plates are provided on the outside with a vertically extending rib 84 adjacent one end and at the other end with a hingedly mounted rib 85, the hingedly mounted rib being connected by longitudinally extending ribs to be connected to longitudinally extending ribs 86 and 87 at the top and bottom. These ribs in turn are connected to a metal cross plate 88 pivotally mounted on a stub axle 89 in a suitable bearing 90 on the machine frame. This stub axle is provided with rigidly mounted bell cranks 91 which are connected through links 92 with the crank arms 81 on the shaft 79 whereby, on the shaft 79 being operated, the side plates 82 and 83 are, 60 through the links 92, moved to a substan-

tially vertical position. It will be noted that the ribs 86 and 87 are suitably bent to extend outwardly in engagement to be secured to the plate 93 in spaced relationship to the sides of the basket. These ribs 70 with a cross plate and a cross rib provide a pivotally mounted frame on which the side plates are supported. Pivotally connected as at 94 to the end of the top rib 86 to this frame is an arm 95, one of a pair, adapted to pivotally support a compressor plate 96. Pivotally secured to the pressure member are the slidably engaging pressure arms 97 provided with coil springs 98 and rigidly mounted on the shaft 79 through 75 the lever arms 99.

In combination with the side plates and supported on extensions of the members 86 is a rear plate 100 adapted, in normal horizontal position of the basket, to assume a perpendicular position forming the end of the basket. This plate 100 is formed in two sections the lower of which 101 is hinged, as hereinafter more fully referred to. The upper portion is provided with roller members 102 on each side adapted to travel on guide or trackways 103 on each side of the frame. This end or rear plate is designed in operation, on the mechanism being tripped, to move from a vertical position inwardly to a slantwise position, while co-acting with the plate 100 and 101 is the displaceable plate or basket 104 formed with a centre rib 105 therein and designed as a whole 90 to form the bottom of the basket in normal horizontal position and, on the basket being operated, to travel upwardly to a vertical position and then to an almost horizontal reversed position, the mechanism for accomplishing this being a pair of arms 106 (see Figure 5) pivotally connected, one on 95 each side, to one end of the basket 104, and a pair of arms 107 pivotally connected, one on each side of the basket 104. The other ends of the arms 106 in turn are pivotally connected as at 108 to the end of the plate 88 while the arms 107 are pivotally connected at their inner ends as at 109 to the ends of the lower horizontal ribs 86 of the frame carrying the side plates. 100

For causing, on the basket mechanism being thrown into gear, the ends of the side plates to move inwardly simultaneous with their assuming a substantially vertical position, I provide slotted arms 110 pivotally mounted at 111 substantially midway of its length on each side of the frame. In the slotted end are rollers 112 adapted to be engaged by the cam members 77, while at the opposite end of these arms are guideways 113 in the form of elongated loops 114. These loops engage with a rounded end of the arms 114 pivotally mounted at 115 and pivotally connected at 116 to a link 117 in turn pivotally connected to one of the verti- 110 115 120 125 130

cal ribs on the side plates, in short forming a hinged connection for these side plates whereby they are moved inwardly at the top when assuming a vertical position, and 5 whereby they automatically return to normal horizontal position through the contraction of this hinged connection and the 10 slidable engagement of the rounded arms 114 with the looped or guideway formed 15 ends of the arms 110. The ends of these arms 110 are pivotally connected through bell crank lever members 118 pivotally mounted at 119 and connected through shock-absorbing coil springs 120 with the 20 pivotally mounted crank arms 91 whereby, on the bottom-forming plate 104 reaching the position as shown in Figure 5, it is automatically impelled, by the action of said springs and the crank arms, to assume its 25 original position. 116' are the holes for adjusting the hinged compressible side plates.

The complete operation of the steeker is as follows:—The machine being hitched up to the binder in well known manner, the 25 basket will be in the horizontal or loading position as illustrated in Figures 2 and 4 with the compressor plate 96 in a vertical position. The operating mechanism for the basket will be inoperative and locked in this position by means of the arm 25 resting on the spring-actuated pin 27 retaining the pawl 23 out of engagement with the clutch teeth 22. At the same time, the cam 70 on the operating shaft 19 for the 30 basket will be in engagement with the pivotally mounted and spring-actuated pawl 69 on the frame which, in turn, is connected through the rod 67 with the arm 65 carrying the lug 64' holding it out of engagement with the spring-actuated arm 62 35 pivotally mounted on the sprocket 36 on the elevator drive shaft 34, thus holding the latter in gear causing, loosely mounted on the forward movement of the machine 40 with the binder, the elevator to operate to receive the sheaves from the binder and deliver them into the basket. On a sufficient number of sheaves to form a stuck being delivered in this manner to the basket, 45 the driver of the machine operates the control lever 29 by pulling it or moving it in any well known manner. This action causes the spring-actuated pin 27 to move inwardly 50 permitting the pivotally mounted arm 25 to drop and automatically causing the pawl 23 to engage with the clutch teeth 22 throwing the shaft 19 and the basket operating mechanism connected therewith into operation.

Simultaneously and automatically with 55 this the cam 70 disengages through the rotation of the shaft 19 with the spring-held pivotally mounted pawl 69, thereby engaging the member 64 with the arm 62 and throwing the elevator operating mechanism 60 out of gear, causing the elevator to stop. As

the shaft 19 rotates with the cam member 70 thereon and while it is performing one revolution until the pawl 69 again engages with the cam 70 and the arm 25 again rests upon the pin 27, the pivotally mounted sides of the basket are operated from a normal horizontal loading position to a substantially vertical position and simultaneously therewith the bottom plate 104 and the end plate 100 are moved from a substantially horizontal and vertical position respectively to an inverted horizontal position and an inwardly slantwise position respectively, as illustrated in Figure 5, when the stuck is deposited. Then, as the rotation of the shaft 19 continues the bottom plate gradually recedes to resume its normal horizontal position as such, the side plates at the same time returning head upwards to normal vertical position, by which time the shaft 19 operating the combined cam and crank shaft 79 in turn operating the basket have completed a single revolution automatically, engaging the arm 25 with the pin 27 to throw the pawl 21 out of engagement with the clutch 23 and, at the same time, automatically locking the mechanism 70' by means of the cam engaging with the spring-held arm 70'. Simultaneously with the automatic engagement of the arm 25, throwing the basket 90 operating mechanism out of gear, the cam 70 automatically engages with the pawl 69 to throw the elevator mechanism, as previously described, into gear and start the 95 elevator.

Concurrently with the operation of the plates forming the basket, as above described, the compressor member or plate 96 pivotally connected to the sides of the basket moves from vertical loading position downwardly between the sides, as they assume a vertical position, to compress the sheaves and then, on the stuck being delivered moves back to normal position with the other elements of the basket. This plate, as previously described, is spring-held to the 100 crank shaft 79.

It should further be noted that the end plate 100 is provided with a hinged lower section to more effectively form a slanting discharge base for the stuck as it is being deposited. This end plate is also provided with runners to more efficiently support it in its travel and designed to engage with tracks on each side of the frame and thus provide 105 more effective support for the assembled sheaves forming the stuck.

The crank shaft 79 and the cranks integral with the stub axles forming the pivotal mounting for the side plates of the basket 110 are pivotally and link connected to one another while the bottom plate is pivotally connected to the side plates and to the stub axle cranks, and the end plate is also pivotally connected to the side plates, this 115 con-

70

75

80

85

90

100

105

110

115

120

125

130

nection imparting a reciprocatory movement to these plates simultaneously with the tilt-able movement of the side plates.

It is also observed that with the rotation 5 of the shaft 19 and the crank shaft 79, when thrown into gear, the cams on the latter engage with rollers 112 causing the pivotally mounted links 110 to move to automatically compress the top ends of the side plates as 10 they assume a vertical position by means of the hinged side arms 114 slidably engaging with said links and, as the basket returns to normal position, the links assume the same position, the hinged arms automatically contracting to return the sides of the basket to 15 normal.

As many changes could be made in the above construction, and many apparently widely different embodiments of my invention, within the scope of the claims, constructed without departing from the spirit or scope thereof, it is intended that all matter contained in the accompanying specification and drawings shall be interpreted 20 as illustrative and not in a limiting sense.

What I claim as my invention is:

1. In a stooking machine and in combination, a tilttable, sheaf receiving, stook forming and depositing basket; an elevator in- 30 operable while the basket is being tilted and operable when the basket is inoperable, mechanism associated with the basket for simultaneously compressing the sheaves and discharging the basket, mechanism associated 35 with the elevator for delivering sheaves from the binder to said basket, a common drive, and a single control for simultaneously throwing one of the mechanisms out of operation and the other mechanism simultaneously and automatically into operation, and mechanism associated with the afore- 40 mentioned mechanisms for simultaneously and automatically throwing one of them out of operation and the other into operation 45 and retaining the one thrown out of operation in an inoperative position until operated by the control.

2. A stooking machine as claimed in claim 1 in which a manual control is provided for 50 simultaneously operating the basket and stopping the elevator, and means associated with the control for automatically and simultaneously stopping the operation of the basket and re-starting the elevator on the basket 55 returning to normal position.

3. The invention according to claim 1 in which the tilttable, sheaf receiving, stook forming and depositing basket comprises pivotally mounted compressible sides adapted to swing from a normal sub- 60 stantially horizontal loading position to a substantially vertical unloading position, pivotally supported bottom and end plates separate from and operatively connected to 65 said sides, a compressing plate adapted to

swing between the sides, means for simultaneously swinging and compressing the sides and reciprocally operating the bottom and end plates, means associated with the compressing plate for simultaneously and 70 reciprocally operating such plate with the operation of the sides, bottom and ends, and spring actuated means for said plates, a swingingly mounted buck plate adapted in normal horizontal position to form an end 75 for the basket and to swing inwardly beneath the basket on the latter assuming a vertical unloading position, rollers on said plate and trackway means on said plate for 80 said rollers.

4. The invention according to claim 1 characterized by the fact that the elevator for delivering sheaves to the basket from the binder comprises a casing, a main drive, a rotatably mounted shaft extending through 85 the casing, chain and sprocket means connecting the main drive with said shaft, a second shaft rotatably mounted in the casing, sprockets and endless conveyor chains on each shaft, a plurality of brackets, cross rods 90 crank-formed at each end pivotally supported in said brackets, trackways in the casing at each end adapted to engage with said rods whereby in operation the rods travel with the chains at substantially right 95 angles thereto and on reaching a predetermined point at the top of the elevator swing downwardly to discharge the sheaves, a receiving table and a guide plate at opposite 100 ends of the elevator.

5. The invention according to claim 1 characterized by the fact that the sheaf receiving stook forming and depositing basket is provided with spring retained bell crank levers associated therewith and operatively 105 connected to the operating mechanism.

6. The invention according to claim 1 characterized by the fact that a longitudinally extending lip or partition is associated with the bottom of the basket for retaining the sheaves in alignment thereon. 110

7. The invention according to claim 1 in which the drive mechanism comprises bevel gears associated with the tractor wheels on the opposite side to the basket drive. 115

8. The invention according to claim 1 characterized by the fact that the mechanism for throwing the elevator out of operation when the basket is forming and depositing the stook and automatically into operation again when the basket returns to normal sheaf receiving position includes a clutch formed with a plurality of spaced slots, a bracket supported pivotally mounted spring actuated pawl adapted to engage with said 120 slots, a shaft rigidly associated with the pawl, a second bracket and an arm pivotally mounted thereon engaging with the pawl, a laterally movable spring actuated pin for the arm adapted to hold the pawl out of engage- 125 130

ment with the clutch member and manually operable means for operating said pin.

9. In a stooking machine a sheaf receiving stook forming and depositing basket comprising in combination a pivotally mounted frame, sides hingedly connected to said frame, a bottom plate pivotally connected to the sides, an end plate operatively connected

to said sides, a spring actuated compressing plate adapted to swing between the sides, a 10 swingingly mounted buck plate, and spring retained bell crank levers pivotally associated with the basket.

In witness whereof I have hereunto set my hand.

NORMAN HOWARD CAUFIELD.
